Fig. 1.

Fig. 2.

To all whom it may concern:

Be it known that we, Rudolph H. Koepf and Benjamin B. du Pont, citizens of the United States, residing at Orange, in the county of New Haven, State of Connecticut, and Pine Orchard, in the county of New Haven, State of Connecticut, respectively, have invented a new, original, and ornamental Design for an Electric Blanket Control Box, of which the following is a specification, reference being had to the accompanying drawing, forming a part thereof.

In the drawing,

Fig. 1 is a front perspective view of an electric blanket control box embodying our new design.

Fig. 2 is a side elevation view of this box.

The dominant features of our design reside in the portions shown in full lines.

We claim:

The ornamental design for an electric blanket control box, substantially as shown and described.
